[57] CLAIM

The ornamental design for a combined multi-section rear view mirror and anti-glare visor, substantially as shown and described.

DESCRIPTION

FIG. 1 is a front elevational view of a combined multi-section rear view mirror and anti-glare visor with the visor turned down to a position in which the face of the mirror is exposed;

FIG. 2 is a front elevational view thereof with the visor turned up into position extending across the face of the mirror;

FIG. 3 is a rear elevational view thereof with the visor in the position of FIG. 2;

FIG. 4 is a top plan view thereof with the visor in the position of FIG. 2;

FIG. 5 is a bottom plan view thereof with the visor in the position of FIG. 2; and

FIG. 6 is an enlarged end elevational view thereof with the visor in the position of FIG. 2, it being understood that the opposite end is substantially a mirror image of that shown.
